E. C. WASHBURN

TRUCK SIDE FRAME

Filed June 24, 1921

UNITED STATES PATENT OFFICE.

EDWIN C. WASHBURN, OF ENGLEWOOD, NEW JERSEY.

TRUCK SIDE FRAME.

Application filed June 24, 1921. Serial No. 480,064.

To all whom it may concern:

Be it known that I, EDWIN C. WASHBURN, a citizen of the United States, residing at Englewood, in the county of Bergen and 5 State of New Jersey, have invented certain new and useful Improvements in Truck Side Frames; and I do hereby declare the following to be a full, clear, and exact description of the invention, such as will enable others skilled in the art to which it 10 pertains to make and use the same.

This invention relates to a truck side frame and also to an improved process of producing the same.

15 It is an object of this invention to provide a side frame, the parts of which are integrally connected and the tension and compression members of which are welded together.

20 It is also an object of this invention to provide a side frame in connection with which a standard "Master Car Builders" journal box can be used.

It is another object of this invention to 25 so construct the side frame and its connection to the journal box that a slight rotative movement of the journal box about the vertical axis relative to the side frame is permitted.

30 It is still a further object of the invention to provide novel means for attaching the brake beam to the bolster columns of the side frame.

These and other objects and advantages 35 of the invention will be fully set forth in the following description made in connection with the accompanying drawings in which like reference characters refer to the same parts throughout the different views, and in which,

Fig. 1 is a view in side elevation of the side frame, a considerable portion thereof being shown in section;

Fig. 2 is a section on the line 2—2 of Fig. 45 1 looking in the direction of the arrows;

Fig. 3 is a section on the line 3—3 of Fig. 1 looking in the direction of the arrows;

Fig. 4 is a view of one end of the side frame similar to that shown in Fig. 1, but showing the side frame attached to a standard journal box; and Fig. 5 is a partial bottom plan view of the end of the frame, as seen in Fig. 1.

55 Referring to the drawings, the side frame is seen to comprise the usual compression

member *a*, the tension member *b*, the bolster column *c*, and the journal boxes *d*, which are connected at the bottoms by the pedestal tie bar *e*. A coupler head or journal box cap member 1 surmounts the journal box *d* and is provided with a cylindrical central socket adapted to fit over a cylindrical boss or projection *d*¹ formed on the journal box. The cap member 1 has a flange 60 extending over the top of said box and is also formed with a portion spaced therefrom forming a socket or cavity 1^a, the largest dimension of which is at its open or inner side. The compression member *a* 65 extends into this socket and the tension member *b* is also bent adjacent its end to extend into the socket in contact with the member *a* and has its extreme end bent upwardly on a reverse curve so that the 70 end of the member is in line with the end of the member *a*. Preferably, the members *a* and *b* are welded together at their contacting end portions to form an integral 75 structure and are formed with a hole *a*¹ 80 extending therethrough. The member 1 is also formed with a hole 1^b in its top side and at its lower side adjacent its inner edge is provided with a groove 1^c.

After the members *a* and *b* have been 85 connected, as described, and fitted into the socket 1^a, molten metal is poured into said socket so as to surround the said members and extend through the mold *a*¹ and into the groove 1^c and also to fill the hole 1^b. The member 1 will, of course, be disposed in suitable cores or molds and the hole 1^b 90 may conveniently be used as a pouring hole for this operation. A cast filler is thus formed in the socket 1^a which securely and permanently unites the parts into one substantially integral structure. A hole is also formed through the top of member 1 to receive a bolt 2, the member *b* also being provided with a hole through which this bolt also passes through the cast filler in the socket 1^a. The hole for the bolt may be drilled through this filler but preferably a core is inserted through the hole in the member *b* and through the member 1 to provide this hole, which core may be removed after the filler is cast into place. The bolt 2 firmly secures the member 1 to the top plate *d*² of the journal box, said plate being provided with a 100 square cavity adapted to receive a nut applied to said bolt.

The journal box *d* has projecting centrally from its bottom portion an integral lug *d*³ and the connecting plank member *e* is formed with an opening somewhat loosely fitting over this lug *d*³ and a wedge member *3* is driven through an opening formed in the lug to hold the member *d* securely thereon, said wedge being held in place by a split key passing through its small end. 5
 10 Bolster columns *c* are formed at their upper ends with openings through which pass the members *a* and said columns are also formed with a recess extending downwardly from said openings along the inner side thereof, filling holes *c*¹ passing from said recess through the wedge portion of the columns. The openings at the top of the columns *c* are provided with holes *c*² extending through the top and bottom portions thereof and the members *a* are also provided with holes extending therethrough substantially in alignment with the holes *c*². After the members *a* have been disposed in the columns in proper relation, molten 25 metal is poured into said openings to fill the space at the top and bottom of the members *a* and the holes therethrough as well as the holes *c*². The columns will at this time be surrounded by suitable mold members 30 to hold the molten metal in proper position, and said metal will not only fill the openings through the top of the columns but the molds will be so arranged that said metal will fill the recess on the inner side of said 35 columns and also pass into and fill the holes *c*¹.

The columns *c* are also provided with openings extending diagonally through their lower portion and the members *b* and *e* are arranged to be disposed in said openings and extend therethrough, said members being formed with aligned holes *e*¹ extending therethrough substantially in the center of said openings. The holes *c*³ also extend vertically downward through the bottoms of the bolster columns *c* and communicate with the openings through the bottom thereof. When the members *b* and *e* are properly disposed in the lower openings in the member *c* suitable cores are placed about these openings and molten metal is poured thereinto which surrounds the members *b* and *e* and fills the hole *e*¹ therethrough. A cast filler is thus formed in said openings which firmly 50 and permanently unites the columns and members *b* and *e* together, which filler also extends into the opening *c*³ which may conveniently be used as a pouring hole. The parts are thus secured substantially integrally in rigid relation. A channel member 55 4 extends transversely of the side frames having its flanged portions disposed upwardly and a plate 5 has flanged portions 5^a riveted to the wedge portion of said channel at the ends thereof, said plate hav-

ing a curved flange at each side contacting with the top of the curved portion of member *b* and also having spaced lugs 5^b at the ends and central portion thereof which extend downwardly a slight distance at each side of the member *b*, as clearly shown in Fig. 3. 70

To secure the brake beam to the bolster columns, a short lug *c*⁴ is cast on the side thereof, and this lug is provided with spaced bored or drilled holes *c*⁵. The holes *c*⁵ are adapted to receive the ends of a U-shaped rod 6 which is firmly held in said holes by the wedge key 7 driven therethrough and through the lugs *c*⁴. 75

The frame is designed so that the same can be used with a standard Master Car Builders' journal box and the use of the frame with such a standard box is shown in Fig. 4. When thus used, the member 1 will be connected to the box by bolts 8 passing through the bolt holes formed in said box and the flange of member 1. Short bolts 9 will also secure the member 1 and the box and tie *e*, together at the inner side. 90 The journal box *d* shown will also be used with the standard type of side frame, but when so used, it will preferably be bolted thereto by bolts passing through the holes at the top and bottom portions thereof, as 95 shown at the right hand end of Fig. 1.

From the above description it will be seen that applicant has provided a simple, strong and efficient structure of side frame, which frame can be made of much lighter construction than frames of the prior art and yet have great abundance of strength. It will be noted that the end of member *b* being bent up into line with the end of member *a*, this end will transmit any tension placed 100 thereon through the filler to the ends of the compression member *a*. The type of fastening in the end of the tension member *b* shown has, in practice, proven to be so efficient that the said members will be ruptured in tension before the end thereof will pull out of the member 1. By having the member 1 extending over the cylindrical projection *d*¹ and the journal bearing connected to 1 by the central bolt 2, it will be 105 noted that a slight rotative movement of the frame in relation to the journal is permitted, there being a small amount of lost motion between the lug *d*³ and the bar *e*. Such a slight rotation is desirable when 110 the trucks are going around a curve. 115

The cast plates at the inner side of the columns *c* form the chafing plates for the bolster and these cast plates are held firmly in place by extending through the holes *c*¹. 120 When the chafing plates have become worn the same may be replaced by being broken away with a hammer and a steel plate secured in their place by rivets extending through the holes *c*¹. 125 130

Heretofore it has been customary to secure the brake beam to the bolster columns by having an apertured lug projecting from the side thereof. With this structure it often happens that in a wreck the lug would be struck and broken off, thus making it necessary to scrap the entire bolster casting. With the structure described, the lug c^4 is quite short and the brake beam is carried by the bent rod 6. If the rod 6 should be subjected to a great shock or strain, the same will be either bent or broken and the lug c^4 will not be injured. Another rod 6 can then be readily procured from stock or from any nearby blacksmith shop and the bolster quickly repaired.

It will, of course, be understood that various changes may be made in the form, details and arrangement of the device without departing from the scope of applicant's invention, which, generally stated, consists in the matter shown and described and set forth in the appended claims.

What is claimed is:

1. A bolster column having thereon a replaceable chafing plate cast thereto and having holding means passed into said bolster column.

2. A bolster column having a chafing plate cast thereto, said plate extending through holes in said bolster column whereby said plate can be replaced by a steel plate riveted through said holes.

3. A side frame structure comprising a bolster column having an opening through its upper end, a compression member passing therethrough, said bolster column having holes therethrough into said opening, and a cast metal filler in said opening and extending into said holes for rigidly securing the bolster and compression member together.

4. The structure set forth in claim 3, said compression member having a hole therethrough through which said cast filler extends.

5. A side frame structure comprising a bolster column having an opening through its upper end and a recess extending down the inner side thereof, compression members, passing through said opening and a cast filler in said opening securing said compression member therein and extending down the side of said bolster column in said recess and forming a chafing plate.

6. A side frame structure comprising a bolster column having an opening through its lower end, a tension and tie member extending therethrough, said bolster column having a hole through its lower side extending into said opening, and a cast filler in said opening surrounding the tension and tie members and extending into said hole.

7. The structure set forth in claim 6, and a hole extending through said tension and

tie members substantially centrally of said opening through which the cast filler extends.

8. A side frame having in combination, a journal box cap having a socket therein, a compression member having its end disposed in said socket and a cast filler surrounding the end of said compression member and securing the same to said cap.

9. A side frame having in combination, a journal box cap having a socket therein, a compression member having its end disposed in said socket, and a tension member also having its end disposed in said socket, and a cast filler in said socket surrounding the ends of said members and connecting the same to said cap.

10. The structure set forth in claim 9, said tension and compression members having a hole therethrough through which the cast filler extends.

11. The structure set forth in claim 9, said journal box cap having a hole through the top thereof through which the said filler extends.

12. The structure set forth in claim 9, the end of the tension member extending beyond the end of the compression member and being upwardly turned in said socket to be in line with the end of said compression member.

13. The structure set forth in claim 9, the end of said tension member being bent downwardly in said socket and having its end portion then bent upwardly in said socket.

14. The structure set forth in claim 9, and a bolt extending through said cap member, said cast filler, the end of said tension member, and centrally through the top of said journal box for securing the cap to said journal box.

15. The structure set forth in claim 9 the ends of the compression member and tension member disposed in said socket being welded together.

16. A side frame structure comprising a journal box having a central lug projecting from the bottom thereof, a tie member having an opening therein adapted to extend over said lug, and means for locking the lug to the tie member.

17. A side frame structure having a bolster column, an angular lug extending from the side thereof having holes therein and a U-shaped rod having its ends disposed in and secured in said holes to form a brake beam attaching member.

18. A side frame structure comprising a bolster column having a short integral lug projecting therefrom having holes therein, and a bent rod extending into one of said holes forming a loop member for the attachment of a brake beam.

19. A side frame comprising a bolster col-

130

4

umn member having an opening in its lower portion, a tension member passing through said opening and having an aperture there-
through communicating with said opening,
5 and a cast metal filler in said opening and passing through said aperture securing said tension member to said column member.

20. The process of constructing a truck side frame consisting in providing compression and tension members, welding the ends of the same together and then securing said ends in a journal box coupling head by cast metal.

21. The process of constructing a side frame which consists in providing compression and tension members and a journal box coupling head, then securing the ends of said compression and tension members together by a cast filler member poured into said coupling head.

22. A side frame having in combination, journal boxes, cap members thereon, compression and tension members having their ends secured in said cap members, and

means connecting said cap members and 25 boxes permitting a relative rotative movement thereof.

23. A side frame having in combination, compression and tension members, means securing the ends of the same together, and 30 journal boxes secured to said means with freedom for slight rotative movement about a vertical axis.

24. A side frame having in combination, journal boxes, compression and tension members secured to the top thereof, and a tie member secured to the bottoms thereof, 35 said journal boxes having freedom for slight rotative movement about a vertical axis.

25. A side frame comprising a bolster column, a compression member, said column having a passage therethrough and having aligned holes in the top and bottom of said passage, and means extending through said holes and through said compression member 40 45 for securing the latter to said column.

In testimony whereof I affix my signature.
EDWIN C. WASHBURN.
